UNITED STATES PATENT OFFICE.

WILLIAM C. TERRY, OF BOSTON, MASSACHUSETTS, ASSIGNOR, BY MESNE ASSIGNMENTS, TO THE MACALLEN COMPANY, OF BOSTON, MASSACHUSETTS, A CORPORATION OF MASSACHUSETTS.

STRAIN-INSULATOR.

No. 882,979.

Specification of Letters Patent. Patented March 24, 1908.

Application filed February 14, 1907. Serial No. 357,269.

To all whom it may concern:

Be it known that I, WILLIAM C. TERRY, a citizen of the United States, residing at Boston, county of Suffolk, State of Massachusetts, have invented a certain new and useful Improvement in Strain-Insulators, of which the following is a specification, reference being had therein to the accompanying drawings.

10 My invention has for its object an improvement in strain insulators and more especially to provide means by which the strain insulator may be readily attached or detached from the wire in which it is placed.

15 It is applicable to various types of strain insulators, but is especially adapted for use with what are known as wooden strain insulators which consist of a piece or bar of wood, to each end of which is fastened a 20 metallic cap for attachment to the wire.

25 The invention will be fully understood from the following description taken in connection with the accompanying drawings, and the novel features thereof are pointed 30 out and clearly defined in the claims at the close of the specification.

Referring to the drawings,—Figure 1 is a 35 side elevation of a strain insulator embodying my invention, showing the wires attached thereto. Fig. 2 is a top plan view of the left hand end of the strain insulator and wire shown in Fig. 1. Fig. 3 is a bottom plan view of the same portion of the insulator. Fig. 4 is a side elevation of the left 40 hand end of Fig. 1, partly in section for convenience of illustration.

Referring now to the drawings,—at A is 45 shown the body of the insulator, which may be wood or similar suitable insulating material.

At B, B, are indicated the caps which are secured to the wooden body in any convenient or well known manner. On each of the caps B, B, is constructed the device 50 which will now be described, by means of which the wire C may be readily attached or detached, as may be required, from the strain insulator. This structure may be cast or otherwise made in a single piece, or may 55 be built up, as may be desired. A pair of side walls 11 and 12, substantially parallel with each other, project from the end of the cap B. These side walls are somewhat trapezoidal in shape, as shown by the elevation in Fig. 1, and are connected by a round

cross piece 13 at their extremity and two other cross pieces or webs 14 and 15 (see Fig. 4), the lower one 15 of which is substantially a half round. These three cross-pieces may be of any desired shape in cross-section, but I consider it preferable to have the portions over which the wire is to pass rounded as shown in the drawings. A transverse opening 16 through the two side walls 11 and 12 is provided.

The interior faces of the two side walls 11 and 12 converge slightly toward each other toward the extreme point of the insulator, that is, toward the left, as seen in Figs. 2 and 3. This convergence is most noticeable in 70 the top plan view in Fig. 2, but also may be seen on the under side of the insulator, (see the bottom plan view, Fig. 3). By this means, the wire is pinched between the two cross walls and thus is held more securely in 75 place.

On the end wall of the cap B or in any other convenient place may be located one or more lugs which may be bent about the wire and which assist to maintain it in place. In 80 the drawings, I have shown two lugs 17 and 18 on the end face of the cap B.

The wire is attached to the insulator in the following manner. The end of the wire is first inserted between the cross pieces 13 and the 85 half round web or cross piece 15, as shown in dotted line in Fig. 4. A U-shaped bend is then made in the lower end of the wire, and the end of the U is pushed up between the two webs 14 and 15 and the body of the cap 90 B, thus passing between two lugs 17 and 18. These lugs are then hammered or pinched over against the wire, as shown in Figs. 2 and 95 3, and the main end of the wire C is straightened out into its normal position, being thus wedged between the two converging faces of 100 the side walls 11 and 12. The two lugs serve to hold the end of the wire C in proper position. The strain placed upon the wire tends to pull the wire C between the converging 105 side walls 11 and 12, and tends to seat the wire against the round cross piece 13. Thereafter, the harder the pull, the more firmly the wire will be wedged in place. By this means, the end of the wire is securely attached to 110 the insulator, but may be readily removed, it only being necessary to lift up the wire to the position shown in dotted lines in Fig. 4, when the U-shaped loop may easily be forced out of connection with the lugs 17 and 18.

While I have described my invention as applied to a wooden strain insulator, it is obvious that it may be applied with equal success to insulators of other forms.

5 What I claim is:

1. The improved insulator provided with an end cap having thereon a pair of side walls converging toward each other and cross pieces between the said side walls, between and about which the wire passes, whereby the strain placed upon the wire tends to pinch the wire between the converging faces of the said side walls.

2. The improved insulator provided with an end cap having thereon two side walls, cross pieces between the said side walls, between and about which the wire to be at-

tached to the insulator passes, and a lug to be bent about the said wire.

3. The improved insulator provided with an end cap having two side walls whose adjacent faces converge in two planes toward each other, and cross pieces between the said side walls, between and about which the wire to be attached to the insulator passes, whereby the strain placed upon the wire tends to pinch the wire between the converging faces of the said side walls.

In testimony whereof I affix my signature, in presence of two witnesses,

WILLIAM C. TERRY.
